TROUSERS

Crescenzo Capuano, Los Angeles, Calif.

Application May 13, 1936, Serial No. 79,514

2 Claims. (Cl. 2-237)

My invention relates to trousers, particularly the construction of the portion fitting around the waist and is applicable to men's trousers or to the so-called slacks worn by women.

An object and feature of my invention is the construction of the trousers at the portion to extend around the waist in which a central, what might be termed panel, portion fits over the front of the abdomen and is separated from the side portions of the trousers by a slit. Each of these side portions is provided with a flap which may be buttoned or otherwise secured over the central panel portion. In addition the flaps may have a short section of a belt attached thereto, which belt sections are provided with a buckle or other fastening, the buckle being designed to clasp in the front portion of the trousers centrally of the panel portion. An advantage of this form of trouser construction is that the trousers may readily be pulled inwardly, that is, tightened or loosened at the waist. The construction also facilitates finishing or changing the stitching where the flap portions are attached to the front panel of the trousers, to give the trousers the desired fit on the wearer. Another detail feature of my invention is that the flaps are provided with buttons which are fastened through button holes at each upper corner of the central panel, these buttons therefore fastened inwardly and being covered or obscured when the trousers are adjusted for wearing. If desired when using these buttons the belt or partial belt may be omitted.

Another feature of my invention relates to the appearance of the trousers, as these are generally pressed with a crease on the front and back, the edge line of the flaps forms a continuation of the line of the crease, thereby giving the effect of the creasing at the front extending from the bottom to the top edge of the waist belt portion of the trousers. In addition, the edges of the flaps thus give a guide line when pressing the trousers to have the crease line up vertically with the edges of the flaps. The flaps are folded toward the fly portion of the trousers so that the crease edge lies closely adjacent the central panel. By means of these flaps the circumferential waist line of the trousers may be adjusted while the central panel remains stationary, the flaps hiding the slits at all times and preserving the center crease of the trousers running from the top to the cuffs at the bottom in a vertical plane. Therefore, the circumferential adjustment of the waistband does not form unsightly wrinkles at any place along the waist line and will present a

neat appearance which is especially desirable in sport trousers which are often worn without any coat.

Another object and feature of my invention is the construction of the front fly portion of the trousers in which a lower portion has the buttons obscured and the upper portion of a central slit at the front has overlapping portions of the panel part of the trousers secured by buttons, the buttons extending through button holes inwardly whereby the buttons are obscured.

My invention is illustrated in connection with the accompanying drawing, in which:

Figure 1 is a front elevation of the trousers with the flaps and belt buckle secured in the position for wearing.

Figure 2 is a similar elevation with the buckle unfastened and the flaps folded sidewise from the central panel.

Figure 3 is a partial front elevation showing the upper portion of the central panel to illustrate the construction of the fly front of the trousers.

Figure 4 is a detail elevation with a side flap folded outwardly.

In the trousers, the waist band portion is indicated by the numeral 11, having an upper edge 12. These trousers may be considered as having a front panel 13 with a slit 14 separating the front panel from the side portions 15, terminating at 16. The side slits 14 are preferably parallel from which a slight fold 17 extends downwardly, this forming a fold line for the side flaps described hereunder.

The side portions 15 of the trousers are provided with flaps 20 which merge with the front panel portion below the bottom of the slit 14. Each of these panels is provided with a button 21 on the inside which secures in a button hole 22 in the central panel adjacent the upper portion thereof. In addition I employ a partial belt construction 25 which has one belt section 26 with a buckle 27 thereon and another belt section 28 with perforations 29 to engage the tongue of the buckle. Each of these belt sections is attached to the inside of one of the flaps by stitching indicated at 30. The front panel also has loops 31 through which the belt sections may be fitted.

If desired, the panel portion of the trousers may have a central slit 35 with an overlap in which the lower portion forms an ordinary fly whereby the buttons 37 are secured to a lining portion of this fly. The outside portion 38 (note Figure 3) of the fly front has buttons 39 secured

on the inside which button through button holes 40 on the opposite side of the fly front, therefore these upper buttons when fastened are inside of the trousers and hence obscured.

5 If desired the trousers may have vertical pleats 41 positioned on the side portions spaced from the flaps and the trousers are illustrated as having side pockets 42.

In putting on trousers and adjusting them 10 when made in accordance with my invention, it is to be understood that if desired these could be made without the fly front in the panel or if this is used, this would be buttoned prior to pulling the panel portion upwardly over the lower 15 portion of the abdomen. The flaps are then folded over the central panel portion and the buttons 21 fastened in the button holes 22 where these are provided. It will be understood that where a partial belt is used that it is not necessary to have these buttons and button holes. The portions of the belt buckles are then fitted in the loops 31 and the buckle may be fastened so that it is centrally located as to the panel, that is, the front of the trousers adjacent the waist 20 band portion. With my invention the edge portion 43 of each flap aligns with the crease 44 25 in the front of the trousers, therefore when the trousers are worn they have the appearance of the crease continuing from the bottom 45 of the trousers to the waist band and to the upper edge 12. Moreover when the trousers are being pressed this edge of each of the flaps forms a guiding 30 line for pressing the crease into the lower portion of the trousers.

35 It will be seen by my invention that as these marginal flaps may be drawn in, that is, towards each other, or allowed to slightly spread apart, that a wearer may readily comfortably adjust the trousers. It will also be apparent that if 40 the stitches joining the panel portion at its marginal edges to the main portion of the trousers, does not give a correct fit, that such stitching may be readily changed without marring the appearance of the trousers at the front.

45 On account of the side flaps 20 overlapping each side of the central panel and as the slight fold 17 partly merges with the crease 44, the upper part of the flap gives the effect of a pleat somewhat similar to the pleat 41. In the fly 50 front construction of Figure 3 the curved seam line 46 strengthens the trousers and the upper button 47 of the fly is above this seam 46.

55 My improved construction of the trousers is especially useful for sport trousers which are often worn without coats. It will be noted that the effective waist line which is adjusted by the flaps 20 in relation to the central panel 13 does not form any wrinkles at any point of the waist line. The flaps 20 ride smoothly past slits 14 60 along the adjacent portion of the central panel, the slits 14 being completely covered at all times as clearly shown in Fig. 1. The only effect such an adjustment will have upon the trousers will be a slight increase or decrease of the fold 17

which ordinarily will not be noticed. By providing the slits 14 in the waist line such smooth adjustment is effected and the undesirable bulging out of the material which would result if no such slits were provided, is avoided.

5 A feature of the fly front construction shown in Fig. 3 is that the seam 46 terminates below the upper button 47 and the button holes 40. Therefore the trousers may be enlarged at the waist portion by setting over the buttons 47 and 39 10 without having any seam showing at this portion of the trousers. Therefore this adds to the neatness of the appearance when it is necessary to increase the waist band measurement of the trousers. Another feature of my invention in regard to the slit 14 leaving a distinct center front panel 13 is that the flaps 20 on the outside of the slits may be completely across such slits as shown in Fig. 1. This construction allows a further adjusting of the waist band either by 15 loosening or tightening by resetting the button holes 22 and the buttons 21. Hence if desired the trousers may be worn without the belt construction 25 having the belt portions 26. Of course when the trousers are made without the belt the loops 31 are omitted. Hence with this form of trousers all of the adjustment for fitting of the waist band may be made at the front of the trousers by an increase or decrease of the 20 overlap of the flaps relative to the vertical slits 14. 25

30 Various changes may be made in the details of the construction without departing from the spirit or scope of the invention as defined by the appended claims.

35 I claim:

1. Trousers having a frontal fly portion and provided with downwardly extending slits equally spaced from the fly portion and forming a central panel therebetween, the side portion of the trousers adjacent the slits each having a folded flap covering the slit and extending partly over the adjacent portion of the central panel, the flap having the folded portion adjacent the slit turned inwardly toward the waist line, the edge of the folded flap being creased and in vertical alignment with the frontal crease of the trousers. 40

2. Trousers having a frontal fly portion and provided with downwardly extending slits equally spaced from the fly portion and forming a central panel therebetween, the side portion of the trousers adjacent the slits each having a folded flap covering the slit and extending partly over the adjacent portion of the central panel, the flap having the folded portion adjacent the slit turned inwardly toward the waist line, the edge of the folded flap being creased and in vertical alignment with the frontal crease of the trousers, and means attached on the flap for longitudinal adjustment in relation to the central panel for changing the length of the effective 45 50 55 60 65 70 75 80 85 90 95 100 waist line of the trousers as desired.

C. CAPUANO.
